UNITED STATES PATENT OFFICE.

CHRISTIAN H. T. HAGELSTEIN, OF BOSTON, MASSACHUSETTS, ASSIGNOR TO THE REECE
BUTTON HOLE MACHINE COMPANY, OF BOSTON, MASSACHUSETTS, A CORPORATION
OF MAINE.

THREAD-CONTROLLING DEVICE FOR SEWING-MACHINES.

1,239,907.

Specification of Letters Patent. Patented Sept. 11, 1917.

Application filed May 5, 1917. Serial No. 166,593.

To all whom it may concern:

Be it known that I, CHRISTIAN H. T. HAGELSTEIN, a citizen of the United States, residing at Boston, county of Suffolk, State of Massachusetts, have invented an Improvement in Thread-Controlling Devices for Sewing-Machines, of which the following description, in connection with the accompanying drawing, is a specification, like characters on the drawing representing like parts.

This invention relates to buttonhole sewing machines and particularly to means for controlling the tension on the upper thread. One familiar type of buttonhole sewing machine is that which includes stitch-forming mechanism, work-holding means, and a rotatable cam for producing a relative movement between the stitch-forming mechanism and work-holding means both during the stitching operation on a buttonhole and also at the end of a stitching operation thereby to carry the work from stitching to button-hole-cutting position. Buttonhole sewing machines of this type are also usually provided with a tension for the thread, and it is desirable that during the stitching operation the tension device should be operative to apply considerable tension to the thread, while at the end of the stitching operation it is desirable to relieve the tension on the thread so that the thread may be readily drawn out if necessary. Furthermore in some machines it is desirable to relieve the tension on the upper thread at each end of the buttonhole.

The object of my present invention is to provide an improved device for releasing the tension on the thread which is controlled directly from the feed cam so that the releasing of the tension on the thread and the application of the tension to the thread may be accomplished in accurate timed relation with the movements of the other parts of the machine.

In order to give an understanding of my invention, I have illustrated in the drawings a selected embodiment thereof which will now be described, after which the novel features will be pointed out in the appended claims.

Figure 1 is a fragmentary sectional view of a buttonhole sewing machine having my improvements applied thereto, said section

being taken approximately on the line 1—1, 55 Fig. 4;

Fig. 2 is an enlarged sectional view through the tension device;

Fig. 3 is a section on the line 3—3, Fig. 2; Fig. 4 is a side view of a portion of a 60 buttonhole sewing machine such as shown in Fig. 1.

The buttonhole sewing machine herein illustrated has a frame 1 carrying the usual stitch-forming mechanism which comprises 65 a needle 2 and its needle-bar 3 for manipulating the upper thread and also an under thread-handling mechanism which is not herein illustrated; work-holding means comprising a clamp-plate 4 and work-clamps 5 70 that are operative to clamp the work to the clamp-plate, and a rotatable feed cam 6 which is constructed to produce a relative movement between the work-holding means and stitch-forming mechanism both during 75 the stitching on a buttonhole and also after the stitching has been completed and the stitch-forming mechanism has been brought to rest thereby to shift the work from stitching to buttonhole-cutting position in which 80 the buttonhole may be cut by the buttonhole cutter 7. Inasmuch as buttonhole-sewing machines having these general features are in common use and are illustrated in various 85 patents, it will not be necessary to further describe the details of construction.

The frame 1 carries a tension device for the upper thread. This tension device is in the form of two friction disks 8 and 9 between which the thread is led and which 90 are loosely mounted on a sleeve 10 that in turn is carried by a split stud 14 secured to the bracket 11 supported on the frame 1. The disk 8 is pressed against the disk 9 thereby to apply the desired tension on the 95 thread by means of a spring 12, one end of which rests against a washer 13 loosely mounted on the sleeve 10, the other end of which is backed by a nut 15 that is screw-threaded on the stud 14. The washer 13 is 100 provided with two apertures 16 separated by a bridge-piece 17. The two halves of the split stud 14 extend through the apertures 16 and the bridge-piece 17 extends through the slot 18 formed in the stud. 19 is a tension-releasing pin which extends axially of the stud and engages the bridge-piece 17 so that movement of the releasing pin to the 105

left, Figs. 1 and 2, will relieve the spring pressure from the disk 8.

20 is an elbow lever pivoted to the bracket 11 at 21, one arm of said lever having a 5 flange 22 adapted to engage the releasing pin so that turning movement of the lever in one direction will release the tension on the thread.

My present invention comprehends a 10 novel device for actuating the lever 20 to relieve the tension on the thread at the proper time in the cycle of operations. I accomplish this herein by the following means:

15 Pivots secured to the elbow-lever 20 is a link 23, the lower end of which is pivotally connected to an arm 24 that is fast on a rod 25 extending through the bed plate 26 of the frame 1 and capable of vertical movement. This rod 25 is acted upon by a spring 27 which tends to move it upwardly and thereby to relieve the tension. This spring constitutes automatically-operative means for relieving the tension on the thread. Se- 20 cured to the lower end of the rod 25 is an 25 arm or finger 28 that is adapted to have contact with the under face of the feed cam 6. This under face of the feed cam is pro- 30 vided with a high portion 29 and a low por- 35 tion 30, said high and low portions being so situated as to engage the finger 28 as the cam rotates. When the high portion 29 of the cam is in engagement with the finger 28, as shown in Fig. 1, then the rod 25 is drawn 40 downwardly against the action of the spring 27 thereby withdrawing the flange 22 of the lever 20 from operative engagement with the releasing pin 19. This allows the spring 15 necessary tension to the thread. When the cam 6 turns so that the low portion 30 is in line with the finger 28, then the rod 25 is per- 45 mitted to rise under the influence of the spring 27 thereby turning the elbow-lever 20 and actuating the releasing pin 19 thereby to relieve the tension on the thread. It will be understood, of course, that the spring 27 is stronger than the spring 12, so that when the low portion 30 of the cam is in line 50 with the finger 28 the spring 27 will overcome the spring 12.

The high and low portions on the cam will be so situated as to cause the tension to be released or applied at the desired times in 55 the cycle of operation. If it is desirable to have the full tension on the thread during the stitching along the sides of the buttonhole and to release the tension at each end of the buttonhole the high and low portions 60 on the cam will be properly placed to produce this result. On the other hand if it is desired to release the tension only at the completion of the stitching on a buttonhole and while the work is being moved from 65 stitching to buttonhole cutting position then

the high and low portions 29 and 30 on the cam will be so situated that the high portion will be in engagement with the finger 28 during the formation of the stitches on the buttonhole, thus permitting the thread to be subjected to the full tension of the tension device, while just after the stitching on a buttonhole has been completed and while the cam is partaking of its turning movement by which it brings the work from stitching 70 to buttonhole-cutting position, the low portion 30 of the cam will come over the finger 28, thus permitting the spring 27 to raise the rod 25 and turn the lever 20 to relieve the tension. By the time that the stitching 75 is begun on the next succeeding buttonhole, the high portion 29 of the cam will again be brought into engagement with the finger 28 thereby to cause the tension to be applied 80 to the thread.

It will be seen that the tension-releasing member is controlled directly from the feed cam and thus the proper timing of the operation of the tension device relative to the movements of the other parts of the machine 90 is secured.

I claim:

1. In a buttonhole sewing machine, the combination with a frame carrying stitch-forming mechanism, of work-holding means, 95 a tension device for the thread, automatically-operative means tending to release the tension, a feed cam for producing relative movement between said stitch-forming mechanism and work-holding means, and 100 means controlled by said cam for holding said automatically-operative means inoperative until the stitching on a buttonhole is completed.

2. In a sewing machine, the combination 105 with a frame carrying stitch-forming mechanism, of work-holding means, a thread tension device, automatically-operative means tending to release the tension, a rotary feed cam for producing relative movement between the stitch-forming mechanism and work-holding means, said feed cam being 110 operative during a portion of its rotation to hold said automatically-operative means inoperative and during another portion of its rotation to permit said automatically-operative means to relieve the tension on the thread.

3. In a buttonhole sewing machine, the combination with a frame carrying stitch-forming mechanism, of work-holding means, a rotary feed cam for producing relative movement between said stitch-forming mechanism and work-holding means, said feed cam having a high portion and a low 125 portion, a tension device for applying tension to the thread, a lever for releasing the tension, a rod connected to said lever, a spring acting on the rod and tending to 130 actuate said lever in a direction to relieve said

the tension, and a finger carried by said rod and adapted to engage the high and low portions of the feed cam as the latter rotates.

4. In a sewing machine, the combination 5 with a frame carrying stitch-forming mechanism, of work-holding means, a tension device for the thread, a spring tending to release the tension, automatically-operative means tending to release the tension, a feed cam for producing relative movement be- 10 tween the stitch-forming mechanism and work-holding means, and means rigid with said cam for holding said automatically-operative means inoperative until the cam is in a predetermined position.

5. In a sewing machine, the combination 15 with a frame carrying stitch-forming mechanism, of work-holding means, a tension device for the thread, a spring tending to release the tension, a feed cam for producing relative movement between said stitch-forming mechanism and work-holding means, and means operating in timed relation with said cam for holding the spring inoperative until the cam is in a predetermined position. 20

In testimony whereof, I have signed my 25 name to this specification.

CHRISTIAN H. T. HAGELSTEIN.
